UNITED STATES PATENT OFFICE.

PETER GRENCIUS, OF MECHANICSVILLE, NEW YORK.

CABINET FOR MUSIC.

1,333,250.

Specification of Letters Patent.

Patented Mar. 9, 1920.

Application filed May 21, 1919. Serial No. 298,760.

To all whom it may concern:

Be it known that I, PETER GRENCIUS, a citizen of Russia, residing at Mechanicsville, county of Saratoga, and State of New York, have invented certain new and useful Improvements in Cabinets for Music, of which the following is a specification.

This invention relates to improvements in music cabinets adapted to receive sheets of music whereby they are held in vertical position.

The principal object of this invention is to provide a music cabinet of neat and pleasing appearance in which sheets of music or like papers may be filed vertically so as to fully utilize the space within the cabinet and from which any desired sheet may be removed without disorder to the remaining sheets.

This and other like objects are attained by the novel construction and combination of parts hereinafter described, and shown in the accompanying drawings, forming a material part of this disclosure, and in which—

Figure 1 is a front elevational view showing a music cabinet made in accordance with the invention, the door being open.

Fig. 2 is a vertical sectional view taken through the same, the door being closed.

Fig. 3 is a transverse sectional view taken on line 3—3 of Fig. 1.

Fig. 4 is an enlarged fragmentary view showing one of the supporting rods.

Fig. 5 is an enlarged fragmentary vertical view showing the separating elements and their arrangement, and

Fig. 6 is a fragmentary side elevational view of the same.

Referring to the drawings, the numeral 10 indicates the sub-base of the structure, the same resting upon feet or supports 11, a drawer 12, provided with a pull 13, being contained within the sub-base for maintaining small articles used in connection with such cabinets.

The upper portion of the cabinet comprises a back wall 15 and side elements 16 secured to a base board 17 at the bottom and a cover plate 18 at the top, while the front may be closed by a door 20 having extending flanged marginal edges 21, the door being secured by hinges 22 and provided with a knob 23 operating a latch engageable with a catch 24 on the opposite side wall of the casing.

A vertical partition 25 extends from the top to the bottom 17 centrally within the structure, forming two equal compartments each of a size to accommodate an ordinary sheet of music.

Also secured between the top and bottom plates, at the front, and near the side walls, are vertical posts 28 and 29 on which are rotatably engaged a plurality of pairs of 65 levers 30, the center pair being the shortest, each succeeding pair increasing in length, as indicated in Figs. 2 and 3.

These levers are maintained at proper distance apart by tubular spacers 31 on 70 the posts, and rigidly engaged with the outer ends of each pair of levers are a succession of plates 32 arranged at right angles to the levers and capable of being folded into the compartments, these plates acting 75 as back-boards or supports for the music sheets.

Fixed upon the outer surfaces of these plates 32, and also upon the door surface 20, are a plurality of paired clip brackets 33, 80 each pair being arranged in staggered relation to the next succeeding pair.

These brackets are adapted to receive and support the horizontal elements 35 of spring wire clips having down-turned portions 36 85 at their extremities and oppositely disposed parallel elements 37 extending from the elements 35, the elements 37 being bent angularly, as at 38, and joined by a cross element 39, the spring clip structure operating to 90 press the music sheets against the plates 32 or door 20, but permitting their upper ends to be sprung out, as best shown in Fig. 5.

In operation, when the door is open, a double cabinet is presented, the inner portion of which contains a plurality of pivoted plates, each capable of swinging outward and fixed upon each plate are a plurality of spring engaging clips capable of holding one or more sheets of music against the 100 plates in such manner that the title is readily observable and which may be easily removed or replaced.

Having thus described my invention what I claim as new and desire to secure by Letters Patent, is—

In a music cabinet of the character described, in combination, a casing having a front door and a single central vertical partition, a pair of vertical posts at the front 110 and inner sides of said casing, a plurality of pairs of levers rotatably engaged on said

posts increasing in length from the center pair, tubular spacers on said posts for maintaining said levers properly spaced, a plurality of plates arranged at the outer ends of each pair of said levers at right angles to the same and adapted to be folded and to act as a support for music sheets, a plurality of paired clip brackets secured to the outer faces of said plates, each pair ar-

ranged in staggered relation to the next succeeding pair, spring wire clips having horizontal elements supported in said brackets, said clips adapted to press the music sheets against said plates and permitting the upper ends of said sheets to be sprung out.

In testimony whereof I have affixed my signature.

PETER GRECHUS.
